FERDINAND P. HUEBNER, JR., OF CAMERON, TEXAS.

ENGINE-STARTING DEVICE.

1,004,263.

Specification of Letters Patent. Patented Sept. 26, 1911.

Application filed January 27, 1911. Serial No. 605,002.

To all whom it may concern:

Be it known that I, FERDINAND P. HUEBNER, Jr., citizen of the United States, residing at Cameron, in the county of Milam and State of Texas, have invented certain new and useful Improvements in Engine-Starting Devices, of which the following is a specification.

This invention pertains to engine starting devices and particularly for engines of the explosive type such as gas and gasolene engines.

The object of the invention is to provide a magneto arranged to be driven fast enough to generate sufficient current to cause a spark and start the engine without the use of batteries.

Another object is the arrangement whereby a driving connection is established between the fly-wheel of the engine and the magneto after the engine is started.

A still further object of the invention is to provide means of the character described that will be strong, durable, efficient, and easy of operation, simple and comparatively inexpensive to construct, and also in which the several parts will not be likely to get out of working order.

With the above and other objects in view, the invention has relation to certain novel features of construction and operation, an example of which is described in this specification and illustrated in the accompanying drawings, wherein:

Figure 1 is a front elevation including the fly-wheel of an engine and illustrating a modified form, Fig. 2 is a side elevation of the same, Fig. 3 is a detail of the pinion employed in the modified form, and Fig. 4 is a detail in section of the brake plunger used in the modified form.

In the drawings the numeral 20 designates the crank shaft of an engine and 21 the fly-wheel fastened thereon. At one side of the fly-wheel standards or supports 22 and 23 are disposed. A table or platform 24 is mounted on the standards. At one side of the table a magneto 25 is located. From the central portion of the magneto a stem 26 depends through and below the table. On the lower end of the stem a handle lever 27 is fixed and by swinging this lever the magneto may be swung. A jam-nut 28 is threaded on the stem and is adapted to bind against the underside of the table and fasten the magneto in position. On the

opposite side of the table from the magneto a shaft 29 is supported in bearings 30 and has on its end adjacent the standard 22, a friction gear 31. The magneto is provided with a friction pinion 32 of such diameter as to be engaged with either the gear 31 or the fly-wheel 21 without engaging the other.

A bearing 33 is mounted on the side of the standard 23 below the table and rotatably supports an arbor 34 on the inner end of which a winding spring 35 is secured. The free end of the winding spring is secured to a bar 36 extending between the standards. On the outer end of the arbor a wheel 37 is secured and a crank handle 38 is also fastened on the arbor by which the latter may be revolved. By turning the handle so as to revolve the wheel 37 to the left with relation to Fig. 1 the spring is wound.

The wheel 37 extends above the shaft 29 and is provided with internal gear teeth 39. A pinion 40 is loosely mounted on the shaft 29 and meshes with the teeth of the wheel 37. This pinion has internal ratchet teeth 41 engaged by a pawl 42 pivotally supported on the shaft 29. When the wheel 37 is revolved in winding the spring the pawl slips over the teeth 41, but when the spring is permitted to unwind and thus revolve the wheel 37 in the opposite direction the pawl will engage in the teeth and transmit rotation to the shaft 29.

For controlling the speed at which the spring unwinds, a governor is provided. This governor comprises a bracket 45 fixed on the shaft 29 and pivotally supporting governor arms 50 having their inner ends engaging a flanged sleeve 55 slidable on the shaft 29. This slidable sleeve is adapted to engage the upper end of a lever 60 pivoted on the standard 22. The lower end of the lever 60 is located to engage a horizontal spring plunger 70 mounted on the standard 22 and adapted to impinge the side of the rim of the friction gear 31. The governor arms are thrown out and move the sleeve toward the bracket 45 whereby the plunger is pressed inward and acts as a brake on the friction gear thus controlling the revolution of the same and indirectly the unwinding of the spring.

To start the engine the magneto 25 is positioned with its pinion 32 in engagement with the gear 31. The spring is then wound and in unwinding will rotate the gear 31 and transmit motion to the magneto. The

magneto will generate sufficient current to cause a spark in the engine (not shown) and start the latter. After the engine is started the magneto is swung so that its pinion 32 is thrown out of engagement with the gear 31 and into engagement with the fly-wheel 21, the engine thus being started without the use of batteries.

What I claim is:—

- 10 1. In an engine starting device, the combination with the fly-wheel of an engine, of a support disposed at one side of the fly-wheel, a friction driving wheel mounted on the support, a spring motor having driving connection with the driving wheel, a magneto movably mounted on the support having a friction pinion disposed between the fly-wheel and the driving wheel of such diameter as to engage with one of said wheels without engaging with the other, and a device for moving the magneto and fastening the same in position.

2. In an engine starting device, a support, a shaft mounted on the support, a friction gear fixed on one end of the shaft, a pinion 25 loosely mounted on the outer end of the shaft and provided with an internal ratchet, a pawl pivoted on the shaft within the pinion and engaging the ratchet thereof, a driving gear wheel mounted on the support 30 and meshing with the pinion, a coiled spring connected to the driving gear and having its outer end attached to the support, and a magneto movably mounted on the support and provided with a friction pinion in 35 juxtaposition to the friction gear.

In testimony whereof I have signed my name to this specification in the presence of two subscribing witnesses.

FERDINAND P. HUEBNER, JR.
